UNITED STATES PATENT OFFICE

EMILE CORNIC, OF PARIS, FRANCE

UMBRELLA

Application filed December 28, 1931, Serial No. 583,506, and in France July 23, 1931.

The present invention has for object improvements in umbrellas, particularly for allowing to make them of strong and elegant construction and to easily manipulate 5 the cup which, in closed position, covers the ends of the ribs and holds them pressed against the umbrella stick.

In a preferred form of construction of the umbrella according to the invention, the 10 cup is rigid with the handle, and the whole can slide on the upper end of the umbrella stick, whilst the ring carrying the ribs is rigidly secured on this stick, as in ordinary umbrellas.

15 A suitable returning device, preferably arranged within the handle, constantly urges the latter towards its lower position, in which the cup is in engagement with the ribs in closed position.

20 This device has the same advantages as those, already known, in which the relative displacement of the ribs and cup is ensured by the sliding movement of the rib-carrying 25 ring on the umbrella stick, viz: a simpler and more elegant assemblage of the handle and cup, and a more positive operation of the latter.

Moreover, a particular advantage of the 30 device according to the invention consists in that the returning spring and the parts slidably mounted on the umbrella stick, arranged at its upper end and no longer at its lower end, do not risk being rusted or wedged by water or mud.

35 The umbrella stick can pass through the handle from end to end so that its upper end projects at the top of this handle.

For releasing the ribs from the ferrule, it 40 thus suffices to hold the handle and to exert with a finger a slight pressure on the upper end of the umbrella stick, so as to cause the latter to slide in the handle by compressing its returning spring; as soon as the ends of 45 the ribs pass the edge of the ferrule, these ribs automatically spread out and are released. This operation can be very easily effected with one hand only.

The accompanying drawing illustrates, 50 by way of example only, an umbrella according to the invention, in elevation with

parts broken away, the fabric being removed.

In the umbrella illustrated, the ribs 2 are pivoted, by means of a wire 3, on the top-notch or ring 1 rigidly secured to the 55 umbrella stick 20.

The lower end of this stick is covered by a protecting cap 15a.

The cup 9 which serves to hold the ends of the ribs is rendered rigid with the handle 11, which is perforated from end to end with an axial hole 11a. The whole is threaded on a rod 21 screwed at 21a to the upper end of the stick 20 of which it forms an extension. This rod 21 terminates, at its upper 60 part, by a knob 21b which projects at the top of the handle.

At its lower part, the handle 11 has a recess 11b forming an extension of the hole 11a, and in which is fitted a socket 22 65 secured to the cup 9 by any suitable means: welding, beading or the like.

A returning spring 23, arranged in the socket 22, is threaded on the rod 21 and compressed between a shoulder 21c of this 70 rod and the bottom 9a of the cup 9, so as to constantly urge the handle towards its lower position, in which the cup covers the ends of the ribs.

The relaxation of the spring 23 is limited 75 by the shoulder 21c abutting against the edge 22a of the socket 22, bent over this shoulder, and by the bottom 9a of the cup 9 abutting against the top of the stick 20.

The pivotal movement of the umbrella 80 stick in the handle is prevented by four ribs 22b of the socket 22, which slide in four notches 21d of the shoulder 21c.

The umbrella being in closed position 85 as illustrated in the drawing, it suffices, for releasing the umbrella ribs from the cup, to exert a pressure on the knob 21b whilst holding the handle 11, so as to cause the stick 20 to slide downwardly by compressing the spring 23. When the displacement 90 is sufficient, the ribs release themselves from the cup, and the knob 21b is no longer pressed upon.

This umbrella can also be provided with 100 an arm-strap 16 mounted in the known,

manner; this arm-strap being connected by two rings 18, 19 to a washer 17 simply held by clamping between the cup 9 and the handle 11.

5 It is obviously possible, without departing from the scope of the invention, to modify in its details, in any suitable manner, the form of construction which has been described above by way of example 10 only, and particularly the method of mounting the handle on the umbrella stick, the returning device interposed between these two elements, the shape, arrangement and mode of assemblage of the push-piece allowing 15 to move the stick relatively to the handle for releasing the ribs from the cup, etc.

I claim:

1. An umbrella, comprising a stick, a rib-carrying ring secured to this stick, ribs pivoted on this ring, a handle slidably mounted on the upper end of the stick, a cup rigid with the handle, a returning device between the handle and the stick, this returning device being adapted to constantly urge the cup towards the ribs, the end of the stick passing through an axial hole perforated from end to end in the handle, and projecting at the top of the latter when the returning device has relaxed.

2. An umbrella comprising a stick, a rib-carrying ring secured to this stick, ribs pivoted on this ring, a handle slidably mounted on the upper end of the stick 35 which through and through, traverses the same through an axial hole and comprising at its lower part a recess forming the extension of its axial hole, a cup rigid with the handle and disposed under the latter, a shoulder rigid with the stick, a spring disposed in the recess of the handle and bearing, at its upper part, upon the shoulder rigid with the stick and, at its lower part, upon the upper face of the cup, the play 40 between the handle and the stick allowed by the height of the recess and that of the spring being such that it allows to engage into or to remove from the cup the upper end of the ribs.

50 3. An umbrella comprising a stick, a rib-carrying ring secured on this stick, ribs pivoted on this ring, a handle slidably mounted on the upper end of the stick which through and through, traverses the same 55 through an axial hole and comprising at its lower part a recess forming an extension of its axial hole, means for preventing every rotation of the handle relatively to the stick, a cup rigid with the handle and disposed under the latter, a shoulder rigid with the stick, a spring disposed in the recess of the handle and bearing, at its upper part, against the shoulder rigid with the stick and, at its lower part, upon the upper face 60 65 of the cup, the play between the handle and

the stick allowed by the height of the recess and that of the spring being such that it allows to engage into or to remove from the cup, the upper end of the ribs.

In testimony whereof I have hereunto affixed my signature.

EMILE CORNIC.
